UNITED STATES PATENT OFFICE.

HANS FRIEDRICH MENCK, OF GROSS-FLOTTBECK, GERMANY, ASSIGNOR TO THE FIRM OF MENCK & HAMBROCK, GESELLSCHAFT MIT BESCHRÄNKTER HAFTUNG, OF ALTONA-OTTENSEN, GERMANY.

EXCAVATOR.

957,234.

Specification of Letters Patent. Patented May 10, 1910.

Application filed February 10, 1909. Serial No. 477,155.

To all whom it may concern:

Be it known that I, HANS FRIEDRICH MENCK, a subject of the German Emperor, and resident of Gross-Flottebeck, Province 5 of Schleswig-Holstein, Prussia, German Empire, have invented certain new and useful Improvements in Excavators, of which the following is a specification.

The present invention has for its object 10 improvements in excavators and relates more particularly to the provision of a braking mechanism in conjunction with the bottom flap of the scoop in order to render it possible to brake or regulate the opening movement of the bottom flap so that the emptying of the scoop can be effected by the operator slowly or quickly according to requirements.

In excavators the scoop is emptied, as is known, by opening the bottom of the scoop 20 which is formed as a flap, after the filled scoop has been swung over the receptacle (truck or the like) intended for the reception of the material. In the constructions heretofore adopted the opening of the bottom flap is effected by releasing a bolt, whereupon the flap suddenly swings downward and the entire contents of the scoop are discharged in one operation. Owing to this arrangement, the truck or the like into 25 which the material is loaded experiences a harmful shock. Now in order to obviate this defect and to empty the scoop gradually and discharge its contents into the truck without shock, in accordance with the present invention the flap is combined with an appropriate braking mechanism (such as a band brake, air or liquid brake or the like) by means of which it is possible to cause the flap to open slowly, that is to say to brake 30 and regulate the opening movement of the flap in the desired manner. The arrangement is also such that during the descent of the scoop the flap automatically recloses so that when the scoop again comes into contact with the ground to be excavated the flap 35 is closed.

The invention is illustrated in the accompanying drawings in which:—

Figure 1 is a side elevation of an excavator constructed in accordance with and embodying the invention, the bottom flap of the scoop being shown open. Fig. 2 is a detail view of the scoop in side elevation to a larger scale, with the bottom flap closed. Fig. 3 is an end elevation and Fig. 4 is a par-

tial sectional plan of Fig. 2. Fig. 5 is a similar view to Fig. 2, and illustrates a modified form of braking mechanism.

The excavator (Fig. 1) is mounted in well known manner on a carriage which traverses 60 on a temporary track. On one end of the frame is a crane 3 which has a circular adjustment on the axial post of the ground plate of the excavator. The crane is provided with a suitable chain- or wire-rope- 65 tackle 4. To the end of the latter is suspended a scoop *a* made of boiler-iron, whose lip *a*¹ is a steel edge preferably with fingers (not shown). Direction is given to the scoop *a* by means of a beam formed of two 70 parallel arms or rails 2 which are jointed to the crane 3. When the scoop has been thrust into the earth, the beam affords a fulcrum on which the scoop rotates when the tackle 4 is wound up on the drum by the 75 action of a steam-engine mounted on the excavator platform.

The engine 5 for operating the beam 2 is mounted on the crane 3.

The scoop *a* which cuts into the ground by 80 means of its lip or cutting edge *a*¹ comprises a bottom flap *b* carried by two yoke pieces *b*¹ rotatable around the shaft *c*. The rear portions of these yoke pieces which are coaxial with the shaft *c* are formed as toothed 85 sectors *b*² and mesh with gear wheels *d* *d*¹ on a shaft *e* the bearings *e*¹ of which are fixed on the arms of the scoop-beam 2. The shaft *e* carries a brake disk *f* the brake band *g* of which is fixed at *g*¹ to the wall of the 90 scoop and to an arm *g*² on a shaft *h*¹ mounted on the rear wall of the scoop. The outwardly projecting end of the shaft *h*¹ carries a lever arm *h* which is connected by means of a link *l* with the arm of a bell crank lever *n* loaded with a weight *m*. At the free end of this bent lever *n*, which is rotatably mounted at *n*¹ to the beam 2 of the scoop, is attached a pull-rope *o* or the like leading to the operator's stand. The weight *m* of the 95 lever *n* tends to exert a tractive effort upon the brake band *g* through the link *l* and the brake lever device *h* *h*¹ and *g*², whereby the disk *f*, the gear wheels *d* *d*¹ and consequently 100 the bottom flap *b* are held in the closed position. If, however, a tractive effort is exerted upon the rope *o* by the operator after the filled scoop has been brought over the receptacle to be loaded, the brake band is 105 released. Owing to the weight of the flap 110

- b*, of the arms *b*¹ and of the load resting upon the said flap of the scoop, this flap *b* will open and the scoop will empty more or less rapidly according to the pull exerted upon 5 the rope *o* and the release of the brake thereby effected; if desired the discharge can be stopped entirely. When the scoop has been emptied and is to be lowered for a fresh cut, the flap closes automatically owing to the 10 sinking of the scoop. For this purpose the brake disk *f* which is loosely mounted on the shaft *e* (Fig. 4), is provided on each side with a spring-controlled pawl *p* or *p*¹. These pawls engage with ratchet wheels *q* or *q*¹ 15 which are rigidly connected with the hubs of the corresponding gear wheels *d* or *d*¹ loose upon the shaft *e*. When the flap opens after the lifting of the scoop upon the release of the brake, the toothed sectors *b*² 20 cause a rotation of the gear wheels *d* *d*¹ in the direction indicated by the arrow in Fig. 2. The ratchet wheels *q* *q*¹ are thus rotated in the direction toward the pawls *p* *p*¹ and the latter carry the brake disk *f* around 25 with them. When the bottom flap *b* is opened the brake disk *f* is coupled with the ratchet wheels *q* *q*¹ of the gearing *d* *d*¹ by the pawls *p* *p*¹, and the gearing, the ratchet wheels and the brake disk then rotate as a 30 whole toward the left hand, relatively to Fig. 2. Upon the descent of the scoop the flap again closes, however, under the influence of gravity, the toothed sectors *b*², the gear wheels *d* *d*¹ and consequently the 35 ratchet wheels *q* *q*¹ rotate in the opposite direction, that is to say to the right hand relatively to Fig. 2 whereby the pawls *p* *p*¹ of the brake disk, which is held by the closed braking mechanism *g*, slide over the ratchet teeth. The tightening of the brake band *g* 40 is effected automatically by the action of the loaded lever *m*, *n* which holds the brake band applied so long as no tractive effort is exerted upon the rope *o*. The bottom flap *b* is closed entirely automatically when the 45 scoop has been emptied, without the necessity for any action on the part of the operator upon the braking mechanism; this mechanism remains applied by the weighted lever *m* *n* after the release of the rope, and during 50 the emptying and lowering of the scoop. When the scoop fills with the material which is being excavated, the latter exerts a pressure against the flap *b*. The flap cannot 55 open however because the pawls *p* *p*¹ of the brake disk *f* do not permit of the rotation of the ratchet wheels, the gear wheels *d* *d*¹ or of the toothed sectors *b*². The brake can be used without any ratchet gear, in which case as shown in Fig. 5 the 60 brake disk *f* is fixed on the shaft *e* and when the scoop descends the brake must be held released until the flap occupies its closed position. This can be effected either by exerting a continuous traction upon the rope

o or by means of special devices which retain the brake lever in the released position in which the brake is not applied and again release it at the proper time.

As shown in Fig. 5 the rope *o* is passed 70 around a roller *r* to which it is fixed. The roller *r* carries on its periphery a locking tooth *r*¹ or a number of such teeth. A locking pawl *s* formed as a two-armed lever bears against the periphery of the roller; its 75 rear arm carries a pin *s*¹ which is guided in a slot *t*¹ in a rod or link *t* pivoted to the yoke *b*¹. The roller *r* is connected by a rope *o*¹ with the brake lever *h*, upon which the weight *m* is likewise arranged. During the 80 excavation the flap *b* is closed, because the brake weight *m* applies the brake. When it is desired to release the brake for the purpose of emptying the raised scoop a tractive effort is exerted upon the rope *o*. This rotates the roller *r* and by means of the connecting rope *o*¹ draws the brake lever *h* and the weight *m* upward. It is now possible to lift the brake weight *m* to such a height as is necessary for slowly opening the flap. 85 When the flap is fully open the rope *o* is again pulled vigorously, thereby raising the weight *m* to its highest position. The brake band is now released fully. The brake weight retains this position because the locking tooth *r*¹ has been seized by the pawl *s* 90 thereby preventing retractive rotation of the roller *r*. The rope *o* can now be released and the brake remains unapplied. If the scoop is now lowered for a fresh cut the scoop flap 95 *b* again closes. Shortly before the flap entirely closes the rod *t* acts in such a manner that owing to its displacement the upper end of its slot strikes against the pin *s*¹ upon the pawl *s* and causes the latter to disengage 100 from the locking tooth *r*¹. The weighted lever *h* *m* in its reversal then applies the brake and the rope *o*¹ again brings the tooth *r*¹ into the position shown in Fig. 5. When 105 the weighted lever is reversed, the rope *o* is re-wound upon the roller *r* in its rotation. The condition obtaining during excavation is thus re-established. If the flap is opened the rod *t* moves upward but owing to its provision with a long slot exerts no influence 110 upon the locking tooth.

I claim:

1. In an excavator, the combination with a swinging support, a scoop mounted thereon, and a bottom hinged to the scoop, of a 120 rotatable member mounted in the support, means operated by the movement of the bottom to rotate said member in opposite directions, and means to exert a braking action on the rotatable member.

2. In an excavator, the combination with a swinging support, a scoop mounted thereon and a bottom hinged to the scoop, of a rotatable member mounted in the support, means connected with the bottom to rotate 130

said member in opposite directions, a brake disk connected with the latter and means to exert a braking action on the disk.

3. In an excavator, the combination with 5 a swinging support, a scoop mounted thereon and a bottom hinged to the scoop, of a rotatable member mounted in the support, rigid means connected with the bottom to rotate said member in opposite directions, a 10 brake disk connected with the latter and means to exert a braking action on the disk.

4. In an excavator, the combination with 15 a swinging support, a scoop mounted thereon, and a bottom hinged to the scoop, of a rotatable member mounted in the support, rigid means connected with the bottom to rotate said member in opposite directions, a 20 brake disk connected with the latter, a brake band surrounding the disk connected with the scoop, and means to actuate the band.

5. In an excavator, the combination with 25 a swinging support, a scoop mounted thereon, and a bottom hinged to the scoop, of a shaft journaled in the support, means connected with the bottom to rotate the shaft in opposite directions, a brake disk, means to fix the latter to the shaft, a brake band surrounding the disk and means to regulate the action of the band.

30 6. In an excavator, the combination with a swinging support, a scoop mounted thereon and a bottom hinged to the scoop, of a shaft journaled in the support, rigid members connected with the bottom to rotate the shaft in opposite directions, a brake disk rotatable on the shaft, means to automatically connect the disk and shaft, a brake band surrounding the disk and means to regulate the action of the band on the shaft.

40 7. In an excavator, the combination with a swinging support, a scoop mounted thereon and a bottom hinged to the scoop, of a gear journaled on the support, a rack on the bottom in mesh with the gear, a brake-member on the support, and a brake member connected with the scoop coöperating with the first mentioned brake member.

45 8. In an excavator, the combination with a swinging support, a scoop mounted thereon and a bottom hinged to the scoop, of gears journaled on the support, racks formed on the bottom in mesh with the gears, a brake disk, means to connect the latter with

the gears, and a brake band surrounding the disk connected with the scoop.

55

9. In an excavator, the combination with a support, a scoop mounted thereon and a bottom hinged on the scoop, of a shaft mounted on said support, a brake-disk on the shaft, gears mounted on the latter, segmental racks connected with the bottom in mesh with the gears and a weight controlled brake-band surrounding the disk, and means to control the action of the weight on the band.

60

65

10. In an excavator, the combination with a support, a scoop mounted thereon and a bottom hinged on the scoop, of a shaft mounted on said support, a brake disk rotatable on the shaft, gears loosely mounted on the latter, segmental racks connected with the bottom in mesh with the gears, means to connect the gears and brake disk and a weight controlled brake-band surrounding the disk, and means to control the action of the weight on the band.

70

75

11. In an excavator, the combination with a support, a scoop mounted thereon, and a bottom hinged on the scoop, of a shaft mounted on said support, a brake disk rotatable on the shaft, gears loosely mounted on the latter, segmental racks connected with the bottom in mesh with the gears, ratchets connected with the gears, pawls on the brake disk adapted to engage the ratchets, and a 80 braking member coöperating with the brake disk.

85

12. In an excavator, the combination with a support, a scoop mounted thereon, and a bottom hinged on the scoop, of a shaft 90 mounted on said support, a brake disk rotatable on the shaft, gears loosely mounted on the latter, segmental racks connected with the bottom in mesh with the gears, ratchets connected with the gears, pawls on the brake 95 disk adapted to engage the ratchets, a brake band surrounding the brake disk connected at one end to the scoop, a brake lever connected to the other end of said band, a weight on the brake lever, and means to 100 counteract the effect of the weight.

HANS FRIEDRICH MENCK.
